TOURNIQUET

Eli Jordan Tucker, Houston, Tex.

Application June 7, 1954, Serial No. 434,873

7 Claims. (Cl. 128—327)

This invention relates to a tourniquet which is readily and positively applicable to an injured member of the body, as a leg, arm, and the like to exert pressure upon such member between the point of injury and the heart until bandaging and stoppage of bleeding may be effected.

It is a primary object of this invention to provide such a tourniquet constructed of rigid, non-corrosive parts positively operable upon application to exert pressure on the part to which applied, such tourniquet being equipped with a gauge assembly which is adapted to increase the pressure of tourniquet application by increments while such pressure can be constantly observed in measurement.

It is another object of this invention to provide a tourniquet having a gauge which increases or diminishes the tourniquet pressure while rendering a measured indication of such pressure.

It is also an object of this invention to provide a tourniquet of this class which is constructed of corrosion resistant, non-infectious parts, as parts of stainless steel and the like, which are operable to positively apply and maintain a tourniquet pressure to an injured member without damaging such member, as by causing tourniquet paralysis or necrosis of the fat tissue at the points where excessive pressure has been applied.

It is a further object of this invention to provide a tourniquet having arcuate, injured member embracing parts which overextend each other at a spaced apart distance whereby a base of force distribution is provided opposite the pivotal connection of the tourniquet arms, thereby obviating the tendency of the tourniquet to roll or slide upon the injured member.

It is still another object of this invention to provide a tourniquet of this class having a gauge pivotally connected to one tourniquet arm and adapted to shoulder upon the other tourniquet arm along an arcuate surface thereof, so that the angle between the gauge and the tourniquet arm to which the gauge is pivotally connected may vary in degree in accordance with the pressure applied and in accordance with the variation in the subtended angle between the tourniquet handles.

Other and further objects will be apparent when the description hereinbelow is considered in connection with the accompanying drawings in which:

Figure 1 is an elevational view of an embodiment of the invention.

Figure 2 is a sectional view taken along line 2—2 of Figure 1.

Figure 3 is a sectional view taken along the line 3—3 of Figure 1.

Referring in detail to the drawings, a tourniquet 10 is shown including tourniquet arms 11 and 12, which are pivotally connected as by a threaded pin or screw 14, with end peened or riveted opposite the head thereof to prevent loss and to maintain assembly. The arms 11 and 12 each include a handle portion 15' and 15, respectively, and arcuate, tourniqueted member embracing portions 16', 16, respectively. In assembly, the portions 16', 16 oppose each other as best indicated in Figure 1, so as to

2

bound a space of substantially oval cross section, as will be the shape of a member of the body after tourniqueting force has been applied thereto. In cross-section, the portions 16', 16 are preferably round to avoid unnecessary angles of force application at points of body contact.

To avoid against the tourniquet rolling or slipping upon the member to which applied, the arcuate portions 16', 16 are curved so that the arm 12, which may overlie the arm 11 at the point of pivotal connection, will provide the arcuate portion 16 which underextends arcuate portion 16', of the arm 11 in the area of the over-crossing part 23, which is spaced from the over-crossing part 23' of the arcuate portion 16'. Thus, on the side of the tourniquet opposite the pivot point, the body member contacting parts of the tourniquet are spaced apart along a line normal to the general plane of the tourniquet, thereby providing a base instead of a point of pressure application opposite such pivot point.

The handle portion 15' extends first in a plane or straight part 17 from the pivot 14 and then has an offset part 17' which forms a connection to a grip 18. The tourniquet handle 15 has a part 19 which extends in a plane or straight from the pivot 14 and then is offset at 19' to form the connection to an arcuate part 20, from which extends the grip 21. The degrees of offset provided by the parts 19' and 17' are such that the grip 18 and the grip 21 will extend past each other if the handles are brought together to completely close the tourniquet. The arcuate part 20 of the handle 15 has slot 21' therein and a gauge 24 has an end part 25 which is pivotally connected at 26 to the part 17 of the arm 11. Such gauge end 25 continues as a mandrel 27 and extends through the slot 21' and outwardly therefrom, the mandrel 27 being threaded over its length 28 from a point adjacent its pivotal connection to the outer end thereof. The threads 29 of such mandrel are of the flat or Acme profile and are particularly tempered for purposes to be described hereinbelow.

A sleeve 30 slides over the mandrel 27 and has a shoulder 31 thereon to bear against the arcuate part 20, 40 while a prong 32 on such sleeve and of lesser width than the slot 21 extends through the slot 21 and has therein a pin 33 extending thereacross to act as a stop against the part 20. This is effected since the pin 33 is of greater length than the transverse width of the slot 21 so that the 45 ends of the pin will bear upon the arcuate part 20 at each side of the slot to thus maintain the sleeve 30 connected to the tourniquet assembly. A set screw 34 extends axially into the end of the prong 32 to bear against the pin 33 and maintain such pin in the prong 32 against sliding laterally.

The sleeve 30 provides an internal shoulder 35 therein to form a seat for a spring 36 which extends around the mandrel. A plunger 37 extends around the mandrel 27 and into the outer end of the sleeve 30, which has a slot 37' therein. A pointer 38 rides upon the sleeve 30 outwardly of the slot 37' and is connected to the inner end of the plunger 37 by means of set screw means 39. A nut 40 is threaded upon the mandrel threads 29. It has end face 41 to bear upon the outer end of plunger 37 and as the nut 40 is further threaded upon the mandrel 27 the plunger 37 will move against the pressure of the spring 36 in direction of the handle 15 when the tourniquet is applied upon a body member.

The application of pressure is obvious, since the resistance of the body member against the tightening of the arcuate portions 16, 16' is sufficiently great to cause the inward motion of the plunger 37 to compress the spring 36 as the nut end bears against the plunger to move with relation to the sleeve 30, with the consequence that the pointer 39 moves with relation to index marks 42 on the sleeve 30 as the spring is compressed. By experimentation and empiricism, the indicia marks 42 are lo-

cated to represent pounds of pressure applied, and thus, as the surgeon or operator tightens up on the nut 40, the movement of the handle 39 inwardly toward the handle 15 indicates accurately the value of the pressure as such pressure is increased.

The shoulder 31 is of a configuration to move downwardly along the outer face of the arcuate part 20 as the pressure is increased, or to recede outwardly along such part as pressure may be decreased, thus permitting the angle between the mandrel 27 and handle 15' to vary as the subtended angle varies between the handles 15 and 15' as the tourniquet is tightened.

In order to permit the removal of the nut 40 and of the other gauge parts, the cap or head 43 on the end of the mandrel 27 is threadably removable therefrom so that the nut 40 may pass over the threads 29. Because the sleeve 30 and the plunger 37 must slide over the threads 29, it is of importance that these threads are especially tempered and of flat or Acme type shape, as stated hereinabove, in order to withstand any abrading or burring which might otherwise occur in continual usage.

The ends 45 and 45' of the arcuate portions 16, 16' respectively, are curved outwardly at an angle to such portions as shown in Figure 1 for the purpose of avoiding abrupt end contact with the body member embraced in the course of installation, operation, or removal.

In providing a tourniquet of this class, objections to the prior art are obviated, such as the objection to the deterioration of pneumatically operated tourniquets constructed of rubber, in which there is likelihood of an unequal application and loss of pressure due to leakage or rubber deterioration. Also the rigidity of the parts on this invention, and the spacing apart of the over-crossing parts of the arcuate portions prevent slippage along the tourniquetted member, which might otherwise take place with such pneumatic devices. Also, it is possible to accurately and positively gauge the pressure applied, increase and decrease such pressure, and observe such pressure with accuracy at all times, as is not the case with other devices of the general class wherein inaccuracies occur in gauges measuring fluid or pneumatic pressures, as in the example where leakage occurs.

Broadly, this invention provides a tourniquet of rigid parts constructed and assembled for easy and positive installation and this invention provides such a tourniquet wherein a gauge may be employed to increase or decrease the application of force to the tourniquetted body member while at the same time indicating the pressure applied. It is asserted that the broad spirit of this invention is not limited to the embodiment described and shown in the drawings attached hereto but many other variations and modifications are stated to fall within the broad scope of such invention and within the broad scope claimed and merited for the appended claims.

What is claimed is:

1. A tourniquet comprising two pivotally connected arms each having handle portions with grips at one end thereof and the pivot supported at the other end thereof and an arcuate, tourniquetted member embracing portion on the opposite side of said pivot from said handle portion, said arms being assembled with arcuate portions in opposition to bound a space of substantially oval cross-section, a gauge pivotally connected to one handle portion and extending past the other handle portion and including a shoulder to bear thereagainst, a force applying member tending to force said other handle portion toward said first handle portion to thereby tighten the grasp of said tourniquetted member embracing portions, an indicia on said gauge, and a pointer movable with said force applying member and with relation to said indicia to indicate the pressure applied by said embracing portions.

2. A tourniquet comprising two pivotally connected arms each having a handle portion and an arcuate, tourniquetted member embracing portion, said arms

being pivotally connected between said handle and arcuate portions and so assembled that as said handles are drawn together said arcuate portions are tightened upon said embraced member, a gauge including a mandrel pivotally connected to one of said handle portions and extending past the other handle portion, a sleeve connected to said other handle portion and extending over said mandrel and having an inner end to bear upon said other handle portion and an internal shoulder adjacent said inner end, a spring extending around said mandrel and bearing inwardly upon said internal shoulder, a slot in the wall of said sleeve, a plunger extending around said mandrel with inner end to bear upon said spring, an indicia on said sleeve, a pointer connected to said plunger through said slot and a nut threadable upon said mandrel to bear inwardly upon said plunger against the tension of said spring to force said handle portions together and tighten the embrace of said arcuate portions as said pointer moves with relation to said indicia to indicate the pressure applied to said embraced member.

3. A tourniquet comprising two pivotally connected arms each having a handle portion and an arcuate, tourniquetted member embracing portion, said arms being pivotally connected between said handle and arcuate portions and so assembled that as said handles are drawn together said arcuate portions more tightly embrace said tourniquetted member, and a gauge connected to one handle portion and bearing against the other handle portion and adapted to apply force to draw said handles together and including an indicia and a pointer movable with relation thereto as said force is applied so that said pointer indicates the pressure applied to said embraced member.

4. A tourniquet comprising two pivotally connected arms each having a handle portion and an arcuate, tourniquetted member embracing portion, said arms being pivotally connected between said handle and arcuate portions and so assembled that as said handles are drawn together said arcuate portions more tightly embrace said tourniquetted member, and a gauge connected to one handle portion and bearing against the other handle portion and adapted to apply force to draw said handles together and including an indicia and a pointer movable with relation thereto as said force is applied so that said pointer indicates the pressure applied to said embraced member, said arcuate portions contacting said embraced member in spaced apart relation on the opposite side thereof from said pivot to prevent said tourniquet from rolling or sliding on said embraced member.

5. A tourniquet comprising two pivotally connected arms each having a handle portion and an arcuate, tourniquetted member embracing portion, said arms being pivotally connected between said handle and arcuate portions and so assembled that as said handles are drawn together said arcuate portions more tightly embrace said tourniquetted member, and a gauge connected to one handle portion and bearing against the other handle portion and adapted to apply force to draw said handles together and including means relatively movable as said force is applied to indicate the pressure applied to said embraced member.

6. A tourniquet comprising two pivotally connected arms each having a handle portion and a tourniquetted member embracing portion, said arms being pivotally connected between said handle and arcuate portions and so assembled that as said handles are drawn together said portions more tightly embrace said tourniquetted member, and means connected to one handle portion and bearing against the other handle portion and including thread engaged means relatively movable to draw said handles together to thereby increase the pressure of said portions on said embraced member, and also including means adapted to indicate the pressure being applied.

7. A tourniquet comprising two pivotally connected arms each having an extending portion and a tourni-

quitted member embracing portion, said arms being pivotally connected between the extending portions and the tourniquetted member embracing portions thereof and so assembled that as said extending portions are drawn together said tourniquetted member embracing portions 5 more tightly embrace said member, said tourniquet including means connected to one extending portion and adjustably bearing against the other extending portion and

adapted to indicate the pressure being applied to said member.
